United States Patent Office

Des. 222,608
Patented Nov. 16, 1971

222,608

JUG

George N. Grosshans, Los Angeles, Calif., and Raymond E. Hobbs, Toledo, Ohio, assignors to Owens-Illinois, Inc., Toledo, Ohio

Filed Dec. 22, 1970, Ser. No. 26,621

Term of patent 14 years

Int. Cl. D9—01

U.S. Cl. D9—42

FIG. 1

FIG. 2

FIG. 3

FIG. 4

FIG. 1 is an elevational view of a jug showing our new design;

FIG. 2 is an elevational view looking from the right of FIG. 1;

FIG. 3 is an elevational view looking from the left of FIG. 1; and

FIG. 4 is a top plan view thereof.

The side opposite that seen in FIG. 1 is a mirror image of the side shown.

We claim:

The ornamental design for a jug, substantially as shown and described.
